UNITED STATES PATENT OFFICE.

ROBERT ERLEBACH, OF BROOKLYN, NEW YORK, ASSIGNOR TO THE PALM BROTHERS COMPANY, OF NEW YORK, N. Y.

DESIGN FOR A PLATE OR SIMILAR ARTICLE.

50,615.

Specification for Design.

Patented Apr. 17, 1917.

Application filed February 24, 1917. Serial No. 150,825. Term of patent 3½ years.

To all whom it may concern:

Be it known that I, ROBERT ERLEBACH, a citizen of the United States, residing at Brooklyn, in the county of Kings and State of New York, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

ROBERT ERLEBACH.

Witnesses:

ALBERT S. BECKER,
V. M. CLARK.
